UNITED STATES PATENT OFFICE.

CARL HALLER, OF CHICAGO, ILLINOIS.

ELECTRIC SIGN.

No. 811,057.

Specification of Letters Patent.

Patented Jan. 30, 1906.

Application filed April 29, 1905. Serial No. 257,981.

To all whom it may concern:

Be it known that I, CARL HALLER, a citizen of the United States, residing at Chicago, in the county of Cook and State of Illinois, have 5 invented a certain new and useful Improvement in Electric Signs, of which the following is a specification.

My invention relates to electric signs of the type wherein the sign-letters are illuminated 10 by incandescent electric light bulbs; and the object of the invention is to provide a sign, which shall be light and durable and require a minimum amount of material and which may be quickly and accurately constructed 15 with a minimum amount of care and skill on the part of the constructor. I attain these objects in the manner illustrated in the accompanying drawings, in which—

Figure 1 is a face view of a portion of a 20 completed sign. Fig. 2 is a perspective view of a letter-outline shell. Fig. 3 is a sectional view of a letter-outline shell and foundation-plate, taken in section on the line 3 3, Fig. 1. Fig. 4 is a fragmentary sectional view similar 25 to Fig. 3, but drawn to an enlarged scale to better show the construction of the parts. Fig. 5 is a fragmentary sectional view similar to Fig. 4, with the exception that a different type of lamp-socket is shown. Fig. 6 is a 30 fragmentary sectional view showing the construction of a letter-outline shell having a modified form of marginal beading.

Similar letters refer to similar parts throughout the several views.

35 The foundation-plate *a* constitutes the foundation of the sign and preferably consists of sheet metal, as shown. Said foundation-plate has a set of apertures *a'* therein for receiving the base of the lamp-bulbs *b*, said 40 apertures being arranged in the form of the letters which are to constitute the sign.

The bulbs *b* are secured in front of the back plate by means of the lamp-sockets *c*, which are partly or completely located behind the foundation-plate. With the type of sockets shown in Figs. 3 and 4, said sockets lie 45 completely behind the foundation-plate; but the type of socket shown in Fig. 5 is also appropriate. In this last-mentioned form a low ring or collar *c'* lies in front of the foundation-plate, but has a threaded portion *c''* adapted to lie behind the foundation-plate and screw into the threaded washer *c'*. The parts are so arranged that when the socket 50 part *c''* is screwed into the washer *c'* the compound socket will be rigidly secured in posi-

tion upon the foundation-plate, with only the collar *c'* lying in front thereof. This collar will ordinarily be hidden from view by the lamp-bulb itself.

In the preferred construction the lamp-sockets and the supply-conductors *d*, which lead thereto, will be housed by a back plate *e* which will be secured to plate *a* at a slight distance behind the same by means of the frame-pieces *f*, as best illustrated in Figs. 3, 4, and 5.

The letter-outline shells *g*, which embody the main features of novelty in this invention, are in themselves open back and front—that is to say, they consist merely of walls forming the contour of the letters and projecting forward from the foundation-plate *a*. These walls are preferably formed of single strips of metal, the width of the strip corresponding to the height of the shell and the length of the strip corresponding to the total perimeter of the letter. In the case of very large sign-letters it may be necessary to solder or otherwise secure together different pieces of metal; but even in such case the entire letter-outline shell will virtually constitute a single piece. As a result of this construction five important results are obtained: First, there is no waste of material by reason of cutting the strip into pieces to be subsequently fastened together; second, there is no waste of time for soldering, riveting, or otherwise fastening such different pieces together; third, there are no joints at the corners of the letter where leaks may occur; fourth, no material is wasted to form either a top or bottom to the letter, and, fifth, the sign is light in weight.

At the back of the letters are formed flanges *h*, whereby the letters may be soldered or riveted to the foundation-plate *a*. 95 These flanges may be turned outward, as shown in Figs. 1 to 5, inclusive, or may be turned inward, as illustrated in Fig. 6. The attachment of the letter to the foundation-plate makes the back of the letter rigid, and it is desirable to stiffen the front of the letter by forming a beading *i* at the outer edge thereof. This beading may be curved in cross-section, as shown in Figs. 1 to 5, inclusive, or may be rectangular, as illustrated in Fig. 6. It is possible, of course, not to form any beading at all at the front of the letter; but this would produce a letter-shell of less rigidity and durability.

Under ordinary circumstances the beading *i* will be formed on the outside of the letter-shell, which will leave the inside unobstructed,

and the letters of the sign will thus exhibit a clear and sharp outline.

By making the inner surface of the letter-shell and inclosed area of the foundation-plate white or of a light color the letters of the sign will, when the lamps are lighted, stand out very clearly; even though only a comparatively small number of lamps are employed.

10. What I claim as new, and desire to secure by Letters Patent, is—

1. An electric sign comprising lamp-sockets, a plate whereto they are attached, said plate being apertured at intervals and said sockets substantially filling said apertures; and a sign-letter open back and front and secured to the front of said plate and laterally inclosing said sockets, said letter consisting of a strip of sheet metal continuous from top to bottom and running peripherally of the letter-outline.

2. An electric sign comprising a plate; a letter-outline shell consisting of a continuous strip of metal running along and forming the outline of the letter, the strip being secured at the rear edge to the front of said plate, and said letter-outline being open back and front; and lamp-sockets secured to said plate within the boundary of the letter-outline substantially as described.

3. An electric sign comprising a foundation-plate, electric-lamp bulbs secured thereto in front thereof, and a letter-outline shell open back and front and secured to said foundation-plate for laterally inclosing said

4. lamp-bulbs, said bulbs being thereby adapted to illuminate the inner surfaces of said shells and such portion of the back plate as is inclosed within the same, and the letter-outline shell consisting of a strip of metal continuous from top to bottom and running peripherally around the letter-outline.

4. In combination, sockets for electric-

lamp bulbs; a plate whereto said sockets are affixed, said plate being apertured at the 45 point of attachment of the sockets and being otherwise imperforate and the sockets being approximately coextensive with the apertures in said plate and the major portion of the socket lying behind said plate; and a 50 sign-letter open back and front and secured to the front of said plate, said sign-letter consisting of a strip of sheet metal continuous from top to bottom and running peripherally around the letter-outline, the said sockets being located within said letter-outline.

5. In an electric sign the combination of a foundation-plate, letter - outline shells consisting of strips of sheet metal bent to letter-outline, the rear edge of each strip being bent 60 to form a flange for attachment to said foundation-plate and the front edge of the strip being beaded over for stiffness; and lamp-sockets secured to said foundation - plate within the letter-shells, the major portion of 65 said sockets lying behind said plate.

6. In an electric sign the combination of a foundation-plate, letter - outline shells consisting of strips of sheet metal bent to letter-outline, the rear edge of each strip being bent 70 to form a flange for attachment to said foundation-plate, and the front edge of the strip being beaded over for stiffness; lamp-sockets secured to said foundation - plate within the letter-shells, the major portion of said sockets 75 lying behind said plate; and a back plate fastened a slight distance behind said foundation-plate for housing said lamp-sockets.

In witness whereof I have hereunto subscribed my name in the presence of two witnesses.

CARL HALLER.
